UNITED STATES PATENT OFFICE

2,604,610

MAGNETRON

Henri Gutton, Paris, France, assignor to Compagnie Generale de Telegraphie Sans Fil, a corporation of France

Application May 1, 1947, Serial No. 745,322
In France December 17, 1940

Section 1, Public Law 690, August 8, 1946
Patent expires December 17, 1960

6 Claims. (Cl. 315—40)

1

This invention relates to magnetrons and magnetron circuit arrangements.

In United States Patent No. 2,147,159 is described a magnetron which can maintain ultra-short waves on a wave length ranging between a few cms. and about 25 cm.

Figure 1 represents diagrammatically the circuit formed by the aforementioned known tube.

Figs. 2 and 3 represent in cut perspective two variants of the tube according to the invention.

The distinguishing feature of the tube described in Patent 2,147,159 is that it sustains oscillations in a circuit entirely built on an anode cylinder. This circuit consists of two parts each containing a certain number of electrodes arranged parallel with the axis of the cylinder and all joined together at one end by a ring, whilst the other ends are free. The parts are interleaved in one another as described.

A circuit so constructed may be diagrammatically represented by a series of lines A₁ B₁, A₂ B₂, Fig. 1, all the ends B₁ B₂ being joined together so that the high frequency potential of these points is zero, whilst A₁ A₂ are, on the contrary, at maximum high frequency potentials. A₁ is at a positive potential, whilst A₂ is at a negative potential. Such a circuit can resonate at a wave length defined by the dimensions A₁ B₁ and A₂ B₂.

It is found by experience that for such system to give a good output, it is necessary that the potential of all the points B₁ and B₂ should be zero. It is therefore necessary to connect all the extremities B₁ and B₂, on one ring and to join the ring B₁ to the ring B₂ through the shortest possible connection. The aforementioned patent describes one arrangement of this nature. The power of the tube is limited by the dissipation of the anode.

This invention seeks to increase the power dissipated whilst still retaining optimum output conditions.

To this end, in accordance with the invention, the surface of the anode is increased by altering its diameter only so that a greater power dissipation is obtained without altering the lateral dimension of the cylinder which determines the value of the wave length. In addition to thus increasing the anode diameter, the invention also envisages the introduction of a large diameter cathode and the replacing of the rings by discs as a means for connecting the extremities of the anode elements.

In order to obtain maximum output, it is necessary that the magnetic field should be of a high value associated with the frequency sustaining the oscillations. With anode cylinders of large diameter and a cathode of small diameter, such as have been used generally hitherto, this results

in a necessity for the tube to be operated at very high voltage, since the magnetic field required is proportional to the square root of the applied voltage.

5 In accordance with this invention, this difficulty is overcome by using a cathode of large diameter, for instance, an oxide cathode indirectly heated. The cut-off magnetic field is then related to the anode potential by the ratio:

$$H = \frac{2R}{R^2 - r_0^2} \sqrt{\frac{2m}{e} V_a}$$

where:

H is the magnetic field,

15 $\frac{e}{m}$ is the ratio of the charge to the mass of the electron,

20 R the anode radius,
r₀ the cathode radius.

The coefficient

$$\frac{2R}{R^2 - r_0^2}$$

may be made as large as desired, thereby enabling the obtaining of a satisfactory ratio of voltage to magnet field facilitating sustention of oscillations under maximum output conditions.

30 In this way it is possible to cause magnetrons of a cathode diameter of 10 mm. to oscillate with ultra-short waves of the order of 10 cm. The cathode has a diameter at least equal to a quarter of the anode diameter.

35 The increase of the anode diameter leads to another difficulty, which is as follows:

The oscillating circuit is entirely on the anodic cylinder, and it is necessary that the potential at the extremities B₁ and B₂ of the circuit should be the same for all electrodes. In proportion as the anodic diameter increases, the rings connecting the points B₁ and B₂ assume dimensions which are no longer negligible, with relation to the wave length. The result is that the ex-

45 tremities B₁ and B₂ are no longer all at the same high frequency potential, that the circuit no longer functions under the conditions above described with reference to Fig. 1 and that it again becomes necessary to reduce the length of the electrodes for a given frequency. With large anode diameters, oscillations might not be sustained.

40 In accordance with this invention, this defect is avoided by using, instead of rings connecting the electrodes together, solid discs. This arrangement of the invention is shown in Fig. 2 which represents, mounted on a base P, a system of electrodes comprising a cathode C of large diameter,

heated by a filament F and surrounded by an anode A composed of alternately interleaved segments. The opposite ends of the two sets of segments are connected by full discs D₁, D₂. That is to say all odd segments are connected together and connected to one circuit and all even segments are connected together and connected to another circuit. The electrode system is contained in the envelope T and a magnetic field in the direction of the cathode C is produced by the poles NS. This makes it possible clearly to define the potential of the extremities of the electrodes connected with the discs, and to retain perfect symmetry. It is then possible to connect the two discs together by a short connection such as L. These discs are necessarily raised to the high potential of the anode. The electrons emitted by the cathode bombard these discs and prevent the tube being blocked by the magnetic field. It is therefore necessary to protect these discs by screens situated inside the tube and raised to the potential of the cathode.

E₁, E₂ represent the screens connected with the potential of the cathode, A₁B₁, A₂B₂ represent the anode and C is the cathode.

It is sometimes advantageous to obtain the same result by mounting the anode electrodes on two discs arranged in a crown or ring D₁ D₂ as shown in Fig. 3 of an outer diameter larger than the anode, and of an inner diameter equal to the anode diameter. Fig. 3 represents the same assembly of elements as Fig. 2 using the same references. Two screens E₁ and E₂ of the same outer diameter as D₁ D₂ are put at zero high frequency potential, the potential of the cathode, for instance. The space between D₁ and E₁ and D₂ and E₂ is so small that the capacity resulting therefrom is large enough to prevent any oscillation of the discs D₁ D₂.

If desired the screens E₁ and E₂ can be subjected to variable potentials of low frequency in order to modulate the anode current of the magnetron, and consequently the high frequency.

Furthermore, since the circumference of the anode is increased, it is necessary in order to maintain good conditions of oscillation to increase the number of electrodes so that the space between two electrodes shall not be too great, for this space is a factor determining conditions for sustaining oscillation.

Finally, it is to be observed that the invention allows the use of powerful cathode with high saturation current, a very great advantage as regards the production of high peak powers in impulse working.

The advantages of the invention are clearly shown in the example given in the table below:

Dimensions and operating conditions	Mag- ne- tron No. 1	Mag- ne- tron No. 2
Working wave length	cm.	12 16
Cathode:		
outer diameter	mm.	6 6
length	mm.	20 23
Anode:		
diameter	mm.	18 18
number of segments		16 16
length of segments	mm.	17 22
Type		Fig. 3 Fig. 3
Power:		
applied	w.	120 150
useful	w.	20 25
peak (4,000 v.)	w.	800 1,000
Magnetic field	g.	600 600
Voltage (Continuous running)	v.	1,500 1,500

The advance constituted by this invention will

be clearly understood by considering that tubes made as known prior to this invention and with a thread like cathode, would have given useful power of 7 watts only in telegraphic working, and from 80-100 watts peak.

What I claim is:

1. A magnetron comprising means for generating a magnetic field, a cathode and an anode, the said cathode extending parallel to said field and having a diameter at least equal to a quarter of the anode diameter, the said anode surrounding the said cathode and being divided into odd and even sets of segments, all odd segments and all even segments being respectively joined together by an end piece and the respective end pieces of the two sets being on opposite sides of the anode.

2. A magnetron comprising means for generating a magnetic field, a cathode and an anode, the said cathode extending parallel to said field and having a diameter at least equal to a quarter of the anode diameter, the said anode surrounding the said cathode and being divided into odd and even sets of segments, all odd segments and all even segments being respectively joined together by an end piece and the respective end pieces of the two sets being on opposite sides of the anode, the diameter and length of the anode being of the same order of magnitude.

3. A magnetron comprising means for generating a magnetic field, a cathode and an anode, the said cathode extending parallel to said field and having a diameter at least equal to a quarter of the anode diameter, the said anode surrounding the said cathode and being divided into odd and even sets of segments, all odd segments and all even segments being respectively joined together by an end disc and the respective end discs of the two sets being on opposite sides of the anode, and two screens connected to the two ends of the cathode and mounted between said cathode and said discs.

4. A magnetron comprising means for generating a magnetic field, a cathode and an anode, the said cathode extending parallel to said field and having a diameter at least equal to a quarter of the anode diameter, the said anode surrounding the said cathode and being divided into odd and even sets of segments, all odd segments and all even segments being respectively joined together by an end ring and the respective end rings of the two sets being on opposite sides of the anode, and two screens connected to the two ends of the cathode and facing said rings, thereby forming with said rings respectively two by-pass capacities for high frequency.

5. A magnetron comprising means for generating a magnetic field, a cathode and an anode, the said cathode extending parallel to said field and having a diameter at least equal to a quarter of the anode diameter, the said anode surrounding the said cathode and divided into odd and even sets of segments, all odd segments and all even segments being respectively joined together by an end piece and the respective end pieces of the two sets being on opposite sides of the anode, and means individual to each of said end pieces for protecting said end pieces against electronic bombardment from the cathode.

6. A magnetron comprising means for generating a magnetic field, a cathode and an anode, the said cathode extending parallel to said field

and having a diameter at least equal to a quarter of the anode diameter, the said anode surrounding the said cathode and divided into odd and even sets of segments, all odd segments and all even segments being respectively joined together by an end piece and the respective end pieces of the two sets being on opposite sides of the anode, and means individually to each of said end pieces for preventing self-oscillation of the said end pieces.
